UNITED STATES PATENT OFFICE.

HENRY C. RICE, OF LOUISIANA, MISSOURI.

DESIGN FOR A COFFEE-POT.

SPECIFICATION forming part of Design No. 14,934, dated April 1, 1884.

Application filed October 5, 1883. Term of patent 14 years.

To all whom it may concern:

Be it known that I, HENRY C. RICE, a citizen of the United States, residing at Louisiana, Pike county, Missouri, have invented or produced a new and original Design for Coffee-Pots, of which the following is a specification, reference being had to the accompanying drawing, forming part hereof, which shows my newly-designed coffee-pot in side elevation.

- 10 A is the lower portion or body of the pot, which is of conical form, and is provided with a handle, *a*, and a spout, *b*, in much the usual way. The spout *b* is tapering, joins the body A at the lower portion thereof, and projects 15 from it at an angle, in the manner common to coffee-pots as heretofore made. On the top of the body A is an upward extension, B, joining the body A at *g* with a bead or beads. This extension B is of the form of an inverted frustum of a cone, the angle of which is but slightly greater than that of the conical body A. The 20 union of the inverted conical extension B at *g* with the conical body A, and the flaring of both parts in both directions from their line of union, produces a pleasing and unique effect. The 25 joint *g* is about on a level with the end of the spout *b*, and is considerably above the base of the handle *a*, to which proportions the novel effect is in part due. The extension B extends

up a distance approximately equal to half its 30 diameter, and on its top is placed the cover C. This cover has a flange, *d*, projecting over the top of the extension B, and the remaining portion of the cover is convex or dome-shaped, and appears wholly above this flange. On top of 35 the cover is a handle, *e*.

My design is equally applicable to tea-pots and other similar receptacles.

I claim—

1. The design for a pot herein shown, the 40 same consisting of the conical body portion A, having handle *a* and spout *b*, with upward extension B joining the body A at *g*, and of inverted conical form.
2. The design for a pot herein shown, the 45 same consisting of the conical body portion A and inverted conical extension B, joining at *g*, as shown, with the cover C, having flange *d*, projecting over the top of the extension B, with a dome-shaped top above said flange. 50

In witness whereof I have hereunto signed my name in the presence of two subscribing witnesses.

HENRY C. RICE.
